BALL-WINDING MACHINE

Hiram N. Huse, Foster, R. I.

Application May 14, 1953; Serial No. 355,129

16 Claims. (Cl. 242—3)

1.

My invention relates to ball-winding machines wherein one or more threads, elastic or non-elastic, are wound under tension upon a core.

The core in my improved machine is held between two opposed, non-rotating heads. Each of these heads carries a plurality of ball-supporting rollers, the face of each of which is preferably covered with a replaceable flexible material which constantly engages the surface of the ball as it is being wound.

This general idea of supporting a ball being wound between two opposed heads is disclosed, for example, in my prior Patent 1,959,780. However, the heads in that patent are rotated, whereas in the instant machine the heads are non-rotatable.

The ball-supporting rollers, above referred to, are rotated on their individual axes. In addition, the mounts for the rollers have certain predetermined movements, and means are provided for separating these movements for purposes which will be discussed hereinafter in detail.

In addition to all of the foregoing, the present invention provides a construction wherein the thread spools are preferably mounted concentric with the longitudinal axis of the machine, these spools as well as the thread guides being rotated about this axis to apply the thread to the ball. In other words, in the winding operation, the thread is revolved about the ball core to apply the thread thereto.

The supporting heads, as above mentioned, are non-rotatable. Means are provided, however, to permit the heads to move apart along the longitudinal axis of the machine to compensate for the gradually increasing diameter of the ball as winding proceeds.

Means are provided also whereby one or either head may be moved along the axis of the machine for a substantial distance to permit of the removal of empty spools and insertion of full spools.

One of the objects of my invention is to provide for varied spacing between successive thread winds on a core. This is done by varying the relation between the cycle speed of the combined rollers and roller supports and the thread winding speed. As a consequence of this construction, it is possible to wind the core initially with open, widely spaced windings, thereby evenly to cover the core with the fewest practicable number of windings. This is very desirable in that it is essential that the relatively soft center or core be maintained as truly spherical as possible. When a substantial thickness of high-tensioned

windings has been applied, so that the ball is now hard and firm and not easily distorted, the windings may be applied closer together to add to the density and hardness of the ball. Near the completion of the winding operation, and this is particularly true when winding golf balls, the spacing between windings may be widened to produce sufficient voids at the ball surface to promote good bonding to the cover, which is usually balata or the like.

This can all be accomplished by maintaining a constant cycle speed and changing the revolving speed of the thread guides. Slow speed of the thread guides will produce open windings, such as are desirable at the beginning of the winding operation and near the finish, while high speed of the thread guides will produce close windings. Identical changes in thread spacing or pattern can be obtained by maintaining constant speed of the thread guides while varying the speed of the cams and ball-supporting rollers.

Another object of my invention is to provide a construction wherein machine wear and vibration are reduced to a minimum. This I accomplish by maintaining the heads stationary except for the movements of the roller units and merely rotating the thread around the ball. This involves rotation of relatively light mechanisms as compared with my prior machine, above referred to, wherein the ball-supporting heads are rotated.

Except for the fast rotation of the thread spools and guides, all movements of the machine are relatively slow.

It will be apparent from the brief outline above set out that the capacity of my improved machine is higher than in the machine of my prior patent referred to and similar machines, and that excessive strains and vibration are not imposed upon the supporting heads, gearing and associated mechanisms.

In the accompanying drawings, Fig. 1 is a part sectional side elevational view of an embodiment of my invention;

Fig. 2 is a part sectional side elevational view of one of the ball-supporting heads;

Fig. 3 is a section taken substantially on the line 3—3 of Fig. 2;

Fig. 4 is an elevational view of one end of the machine; and

Fig. 5 is an elevational view of speed-changing apparatus suitable for use with my machine.

Referring to the drawings in detail, 2 designates the two opposed heads of the machine, the spindles therefor being designated 4. The mounting spindles 4 are in axial alignment with

each other and extend into supports 6, so that the heads are in axial alignment.

As distinguished from the machine of my prior patent above referred to, the heads 2 are non-rotatable. The only movement imparted to these heads, except for the movement of the ball-supporting rollers and roller supports, is an end-wise bodily movement axially of the machine, to compensate for the increasing diameter of a ball being wound and to permit one head and its associated mechanism to be moved away from the other sufficiently to provide for renewing the thread spools, all of which will be explained in detail hereinafter.

The heads 2 are identical in construction, except that the mechanisms are right and left hand, so that a description of one head applies to both.

Referring to Figs. 1 and 2 of the drawings, it will be seen that the spindle 4 of each head is hollow, and extending through the spindle and into the head itself are two shafts, a solid shaft 8 and quill 10, the latter extending between the head spindle 4 and the solid shaft 8. For clarity of description, the shaft 8 will be referred to hereinafter as a roller spindle drive shaft, while the quill 10 will be referred to as a cam shaft.

On the inner end of the roller spindle drive shaft 8 is a spindle drive gear 12.

Each head 2 is equipped with a plurality of ball-supporting rollers 14 for supporting the ball 16 as it is being wound, each roller preferably being provided with a rubber cap 18, similar to the cushion caps 70 of my prior Patent 2,076,565. These caps are readily replaceable and so constructed as to slip around on the surface of the rollers 14 to turn and twist with the ball, thereby preventing abrasion of the ball surface.

An intermittently oscillated roller support 20, mounted in the forward or inner end of the head, is provided for each roller 14.

A spindle 22, extending axially of the machine through each roller support 20, is provided for each roller 14. Each spindle at its end remote from the rollers is provided with a gear 24, in constant mesh with the spindle drive gear 12 previously mentioned. On the other end of each of the spindles 22 is a bevel gear 26, meshing with bevel gear 28 on stub shaft 30, which directly mounts the rollers. These stub shafts 30 are inclined to the longitudinal axis of the machine, as will be seen from Fig. 2.

It will be apparent, therefore, that rotation of the spindle drive shaft 8 of each head will effect simultaneous rotation of all of the rollers 14 in the same direction. The drive is by way of shaft 8, gears 12 and 24, spindle 22, gears 26 and 28, and shaft 30.

In addition to rotating each roller 14 on its individual axis, I provide for intermittent oscillation of the supports 20 in parallel relation on their individual axes. These roller supports 20 are mounted in a spider 32, universally mounted on a ball and socket arrangement 34. This spider is provided with pintles 36, extending into rings 38, wherein the roller supports are mounted.

Mounted in the inner end of the roller spindle drive shaft 8 and projecting therefrom is a stub shaft 40, carrying a compound cone gear 42. Each roller support at the end which lies inside the head is reduced in diameter, this portion carrying a gear 44. These gears 44 mesh with one part of the compound cone gear 42. The other part of gear 42 meshes with a gear segment 46, carried by cam lever 48, fulcrumed on pin 50. 75 rollers 14 rotate in fixed relation with the sup-

The cam lever 48 carries a cam roller 52, which revolves on pin 53 and follows the cam track 54 of the cam 56, which is keyed to the cam shaft 10.

It will be apparent that this provides for rocking or oscillating the roller supports 20 simultaneously and intermittently in parallel relation about their individual axes in accordance with the shape of the cam track 54 of cam 56, from which the gear segment 46 receives its motion.

Adjacent the outer end of each of the cam drive shafts 10 are gears 58 and 60, meshing with broad-faced drive gears 62 and 64, respectively. The gear 58 is keyed to the cam drive shaft, while gear 60 is not, so that the gear 60 is free to rotate at a different speed from 58. The gears 62 and 64 are keyed to a main drive shaft 66, driven from any suitable motor.

The spindle drive shafts 8 are free to rotate in the quill or tubular cam drive shaft 10, and at the extreme outer end of each of the spindle drive shafts is a pinion 68, meshing with a gear segment 70, keyed to fulcrum pin 72, mounted in gear 60. The fulcrum pin 72 is free to turn in gear 60 and projects beyond the inner face of this gear. Integral with this pin or rigidly secured thereto is cam lever arm 74, carrying cam follower roller 76, riding in cam track 78, provided in gear 58.

As hereinabove set out, the two heads of the machine are identical in construction, except that they are in opposite hands, so that any action taking place in one head at any instant is simultaneously being duplicated in the opposite hand in the other head.

From the description thus far given, it will be appreciated that cam drive shaft 10 will be rotated through the medium of gears 62 and 58 to impart rotation to the cam 56. Rotation of this cam will effect rocking of the cam lever 48 by reason of the shape of the cam track 54, thereby to drive or rotate the roller supports 20 about their individual axes in parallel relation first in one direction and then in the other, the cam track 54 being so shaped that there is an appreciable dwell between reversals of the roller support movements.

As above pointed out, the ball-supporting rollers 14 are driven from drive shaft 8, which has been referred to as a roller spindle drive shaft. The function of the cam or rather the cam track 78 in the face of gear 58 and its associated elements is to cause the spindle drive shaft 8 and, hence, the spindles 22 and the ball-supporting rollers 14 to rotate about their individual axes in a constant direction during the periods the roller supports 20 are "dwelling" the ball-supporting rollers 14 deviating from this common direction due to the action of the cam lever 74, whereby the ball-supporting rollers 14 become fixed in relation to the roller supports 20 during rotation of the roller supports in either direction in parallel relation about their individual axes.

Normally, the ball-supporting and driving rollers 14 turn in one common direction due to the differential movement of the gears 58 and 60. The only departure from this action is when the roller supports are rotated in parallel relation about their individual axes to alter or vary the setting of the rollers relatively to the head. Consequently, the track 78 is so shaped that, whenever the roller supports 20 are oscillated in either direction in parallel relation about their individual axes, the ball-supporting and driving rollers 14 rotate in fixed relation with the sup-

ports, these rollers at all other times rotating in a constant direction.

In other words, means are provided for effecting deviation from the normal rotation of the ball-supporting and driving rollers 14 to cause them to move integrally with the roller supports 20 whenever the roller supports are oscillated in parallel relation on their individual axes in either direction.

The spindle 4 of each of the heads 2, as above pointed out, is supported in a support bearing 6. These spindles are non-rotatable but have movement longitudinally in the bearing 6 to permit the heads 2 to move apart as the ball, held between them, increases in diameter. Accordingly, each spindle is provided with a keyway or slot 80 and extending into this keyway or slot is a set screw 82, provided with lock nut 84. The set screw acts as a key permitting the head spindles to be moved longitudinally but preventing their rotation.

As has been previously pointed out, not only must provision be made to enable the two heads of the machine to move away from each other automatically during the winding of the ball as the ball gradually increases in diameter, but it becomes necessary to move one head and its associated mechanism, including bearing support 6, away from the other head and associated mechanism, to permit the thread supply spools to be replaced. Accordingly, the bearing support 6 at the right-hand end of Fig. 1 of the drawings has been shown mounted in a guide 86; which is provided in the base of the machine and normally is held in fixed position in this guide by screws 88. This construction will be referred to again later on.

Each head spindle is equipped with a yoke 90, and each of these yokes, which is in the form of a bell crank lever, is provided with an arm 92; each of these arms at their free ends carrying meshing gear segments 94.

To each of the gear segments is secured a link 96 and a cross-link 98; from which is suspended a weight 100. The function of the weight 100 and associated mechanism, just described, is to hold the caps 18 of the ball-supporting and driving rollers 14 against the ball 16 with the proper pressure. As the ball increases in diameter, it simply forces the two heads apart, raising the weight 100. It is to be noted that, as the heads move apart, the gears 58 and 60 move with them, remaining in mesh with the gears 62 and 64; however, which, as shown, are broad-faced gears for this purpose.

As pointed out at the outset of this description, the machine of this invention differs very materially from machines of the type shown in my prior Patent 2,076,565, in that the ball-supporting heads 2 are non-rotatable, and in that thread guides, rotatable about the ball, are provided to wind the thread about the ball. The thread supply spools as presently pointed out are rotatable about the longitudinal axis of the machine, positively driven thread guides being provided which also rotate about the longitudinal axis of the machine for taking the thread off the spools and guiding it to and carrying it about the ball.

The fixtures for mounting the thread spools and the thread-guiding mechanism will now be described.

From an inspection of Fig. 1 of the drawings, it will be seen that 102 designates what may be termed a driving pulley, rotatable on anti-friction bearings 104, provided at each bearing support 6. Each pulley may be driven through a

belt 106 or preferably by a chain or other convenient drive from a suitable driving motor, which is preferably variable speed. The motor has been omitted from the drawings for clarity. Secured to the inner face of the pulley 102 is a spool mounting fixture 108. This fixture is hollow, surrounds the head 2, and is stepped as shown at 110 to accommodate a plurality of thread spools. This fixture 108 is rigidly secured to the pulley 102 and is coaxial therewith. Disposed about the face of the spool mounting fixture are a plurality of rollers 109 held in place by steel rings 111.

The thread spools are designated 112 and 114. These spools are a friction fit on the steel rings 111 and are coaxial with the pulley 102. In other words, the pulley and spools rotate about the longitudinal axis of the machine, the spools surrounding the non-rotatable heads 2. Screwed into the inner end of each spool fixture is a ring 118. This is a retaining ring for retaining the spools against endwise movement on the fixture. It will be appreciated that other arrangements may be provided for this purpose.

It will be seen, therefore, that I have provided for the positive rotation of the thread spool mounts about the longitudinal axis of the machine, and that the thread spools themselves are allowed free movement of rotation, provided by rollers 109, to unwind the thread from the spools at a suitable rate to maintain the proper back tension in the thread.

To guide threads from the spools to the ball, I provide two thread guide arms at each head, rigid with the pulley 102, the two arms of each pair being disposed diametrically opposite each other. Each of these thread guides comprises an arm 120, extending radially relatively to the spool mounts and then forwardly, so that their outer ends, that is, the ends remote from the spool mounts, are roughly in line with the ball center being wound. One of the arms 120 is equipped with two pulleys 122 and 124, while the other is equipped with pulleys 126 and 128.

Removably secured to the extreme outer end of each of the arms 120 is an arm 129, extending radially of the spool mounts toward the ball. Each of the arms 129 carries a pulley 130.

The thread from the spool 112 passes over the pulley 128 and then is looped at least once about the brake or tension pulley 128 at the extremity of arm 120 and from thence passes over pulley 130 to the ball 16. The thread from spool 114 passes directly to brake or tension pulley 124 and is looped at least once around this pulley and then passes around the corresponding pulley 130 to the ball 16.

Pulleys 124 and 128 are each provided with a brake, which has been designated 132. These brakes may take any convenient form and are provided for the purpose of putting slight pressure on the pulleys to resist their turning freely, thereby to provide for tensioning of the thread as it is wound upon the ball 16.

As noted, the arms 129 are removably attached to arms 120, and in this connection it is to be noted are held in place on the arms 120 by set screw 136. These arms 129 are made removable, so that, when changing thread spools, the arms may be removed from the arms 120 and the spools slipped endwise off their respective mounts.

As already explained, in the initial setting up of the machine the heads 2 will be held by the weight 100 in position, to maintain caps 18 of the ball-supporting rollers 14 in contact with the surface of the ball being wound, and as the

ball increases in diameter, the heads 2 will be pushed apart automatically by the ball itself, carrying the gears 58 and 60 along with them. However, when it becomes necessary to replace a thread spool, not only must the heads 2 be separated a greater distance than is required to accommodate the ball itself, but the spool mounts and thread guides must be moved also. Upon reference to Fig. 1 it will be seen that, to change the thread spools, it is merely necessary to loosen the screws 88 at the bottom of the bearing support at the right hand end of Fig. 1 and to remove the screw 138 in the yoke arm 90, this arm being made in two pieces so that, when the screw 138 is removed, the upper part of the arm is free to be moved to the right. The drive shaft 66 has a long keyway 140, so that the entire mechanism to the right of the ball 16, as viewed in Fig. 1, may be moved a sufficient distance away from the other half of the machine to permit the removal of arms 128 and retaining rings 118, so that the spools on either or both heads may be slipped off their respective mounts and replaced with full spools.

Reverting to the thread guides, it is to be understood that each half of the machine is equipped with a pair of these guides, as already explained, the guides at one side of the machine being set diametrically opposite each other, the guides in the other half of the machine being set diametrically opposite each other but rotated 90° from the position of the guides on the first half of the machine. This makes for a balanced machine and eliminates vibration. This is important inasmuch as the thread guides are rotated at very high speed when the machine is in operation, and, by reducing or eliminating vibration, wear on the machine is reduced to a minimum.

From all of the foregoing it will be seen that I have provided a machine for the winding of balls wherein the ball, as it is being wound, is held between opposed sets of capped rollers, which are in contact with the surface of the ball. These rollers are driven rollers and, as above explained, each roller is mounted in a support which is given an intermittent rotative or oscillatory movement, these supports being rotated or oscillated about their individual axes in parallel relation first in one direction and then in the other with an appreciable dwell between reversals as determined by the cam 54. It will be understood also that the cam mechanisms at the outer ends of the machine are so arranged that the ball-supporting and driving rollers 14 are rotated about their individual axes in a constant direction during the periods the roller supports 20 are dwelling, the rollers deviating from this common or constant direction, whereby the rollers become fixed in relation to the roller supports 20, during rotation of the roller supports in either direction in parallel relation about their individual axes.

It will be understood also that by varying the speed ratio between the shaft 66 and the pulleys 102 the winding pattern on the ball may be varied. This permits the application of open windings upon the relatively soft ball center or core for the purpose of conveniently distributing the least number of windings to cover the core. This is at the start of the winding operation and promotes holding the center in the form of a true sphere. When a substantial thickness of these widely spaced tensioned windings have been applied to the ball core, so that distorting

of the core is no longer likely, then the windings may be spaced closer together, thereby adding to the density and hardness of the ball. Near the completion of the winding operation, the spacing between windings may be again widened, so as to assure good bonding to the cover which is applied to the finished ball. It will be understood that the different spacings between the windings, that is to say, the variations just referred to, are readily accomplished by, for example, maintaining a constant cycle speed with respect to gears 58, 60, 62, and 64 while varying the speed of the guide arms 120 by varying the speed of the belts or chains 106, which drive the guide arms. If this speed is increased, this, of course, will produce close windings. On the other hand, relatively slow speed of the thread guides will produce open windings. The ability to vary the relative speeds of the thread guide arms and the cycle speed of the rest of the machine has another advantage in that it enables the machine to be adjusted readily to wind different types and cross-sections of thread or tape. I might add, as already indicated, that vibration in my machine has been reduced to a minimum in that, except for the fast rotation of the thread spools and their guides, all movements of the machine are relatively slow. As a result of this construction and because of the fact that the guide arms are balanced, not only is excessive vibration avoided, as already mentioned, but the machine may be operated at very high speed, so that its capacity is very high, without imposing severe strain and vibration on the heads, the differential gearing and associated mechanisms.

As will be appreciated by those skilled in this art, identical results are obtained, so far as winding pattern is concerned, by varying the speed of the motor which drives the main drive shaft 66 or by varying the speed of the motor which drives the belts 106 and, hence, the guide arms, or by maintaining constant speed of the thread guide arms and altering the speed of the roller supports and rollers.

In this connection I have shown an arrangement at the right-hand side of Fig. 1 for effecting these variations in speed automatically. This arrangement merely comprises a plurality of fixed contacts 150, 151, and 152, mounted, for example, to the fixed bearing support 6. Cooperating with these contacts is a movable contact 154, mounted on the head spindle 4. These contacts are connected in well known fashion to an electric motor, which may be driving either the drive shaft 66 or the pulleys 102. Initially the movable contact 154 will be in engagement with fixed contact 150 for slow speed of the driving motor, thereby to produce an open weave initially upon the ball core. As the ball increases in diameter and spindles 4 move outwardly, fixed contact 151 will be engaged to increase the speed of the driving motor to produce a closed weave, and when the ball diameter has further increased to a predetermined amount, fixed contact 152 will be engaged again to slow down the motor and produce an open weave.

It will be appreciated that this speed control construction is merely illustrative inasmuch as, obviously, other well known constructions may be used with equal facility. It is to be understood that the spacing and number of fixed contacts may be varied as desired, to vary the number of wraps applied in each pattern and to vary the number of times the winding pattern may be altered and the extent to which it is altered on

each change and that additional contacts may be used to stop both motors and terminate the winding operation.

In Fig. 5 I have illustrated an arrangement whereby the speed ratio between shaft 66, which may be running at constant speed, and the belts 106, which drive the pulleys 102, may readily be varied. This arrangement comprises two pairs of pulleys 160 and 162, connected by belt 184. The pulleys 160 are slidably mounted on shaft 66, which carries pulleys 168 for driving the pulleys 102 through the belts 106. The pulleys 162 are slidably mounted on the shaft 66.

Sliding of the pulleys 160 and 162 simultaneously on their respective shafts is effected through levers 170 and 172, fulcrumed at 174, these levers being pivoted through toggle mechanism 176. The rod 178 is the actuating member for the toggle, and, by adjusting this rod manually, the pulleys 160 may be separated while the pulleys 162 are being pushed together, or vice versa. Each pair of pulleys forms a V, so that varying the setting of these pulleys will vary the speed of shaft 66 with respect to shaft 66, thereby to vary the speed ratio between belts 106 and shaft 66.

It is to be understood furthermore that changes may be made in the details of construction and arrangement of parts hereinabove described within the purview of my invention.

What I claim is:

1. In a ball-winding machine, the combination of a pair of opposed non-rotatable heads; a supporting spindle for each head, said spindles being in axial alignment; ball-supporting and driving rollers carried by said heads; an oscillatable support for each roller; means for rotating said rollers about their individual axes, and means for intermittently oscillating said roller supports, for rotating the ball successively on a plurality of axes; a fixed thread spool mount for supporting a spool of evenly distributed thread at all times concentric with the longitudinal axes of the said spindles and in fixed relation to the center of the ball being wound; a thread guide rotatable about the said longitudinal axes for guiding thread from the supply spool to and about the ball; and mounts for the heads permitting the heads to separate independently of the spool mount and thread guide, to compensate for the gradual increase in the ball diameter, said thread spool mount and thread guide being movable as a unit with one of the heads to permit of their unitary movement away from the other head a sufficient distance to permit of the replacement of the thread spool.

2. In a ball-winding machine, the combination of a pair of non-rotatable winding heads; a mounting spindle for each head, said spindles being in axial alignment; ball-driving rollers carried by said heads; means for normally rotating said rollers in a common direction about individual axes; supports for said rollers carried by said heads; cam-controlled means for intermittently effecting rotation of said supports simultaneously first in one direction and then in the opposite direction in parallel relation on their individual axes; cam-controlled means for interrupting the normal rotation of the rollers in timed relation to rotation of the roller supports, whereby the rollers rotate integrally with the supports during rotation of the supports; a thread supply spool of evenly distributed thread for rotation about the longitudinal axis of the machine, and a thread guide rotatable about the center line of the heads for carrying thread from the spool about the ball during the movement imparted to the ball by the said rollers and roller supports.

3. In a ball-winding machine, the combination of a pair of opposed non-rotatable winding heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

4. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

5. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

6. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

7. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

8. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

9. In a ball-winding machine, the combination of a pair of opposed non-rotatable heads; a mounting spindle for each head, said spindles being in axial alignment; ball-supporting and driving rollers carried by each head, said heads being movable axially relatively to said fixture; a thread guide carried by each fixture and rotatable about the said heads to carry thread about the ball supported by said rollers; a driven shaft extending through each of said spindles for driving the ball-supporting rollers; gearing for said shafts; and a mount for one of said fixtures, the associated head, thread guide, and gearing whereby the same can be moved axially of the machine away from the opposed head to permit of removal and replacement of the thread spool.

11

ture surrounding said head; rollers on the face of said fixture; a ring surrounding said rollers; and a thread spool telescoping said ring with a friction fit.

7. In a ball-winding machine, the combination of a non-rotatable head; a bearing support therefor; a rotatable member mounted for rotation on said bearing support; a spool-mounting fixture carried by the rotatable member and surrounding said head; rollers on the face of said fixture; a ring surrounding the rollers; and a thread spool telescoping the ring, thereby to provide for slippage of the spools in their normal rotation.

8. In a ball-winding machine, the combination of a non-rotatable head; a bearing support therefor; a rotatable member mounted for rotation on said bearing support about the center line of said head, said head being movable longitudinally in said support relatively to said rotatable member; a spool-mounting fixture carried by said rotatable member, said fixture surrounding the head; and a ring secured to the end of the spool-mounting fixture to overlap the end of a spool carried by the fixture to prevent unintentional removal of the spool from the fixture.

9. In a ball-winding machine, the combination of a non-rotatable head; a bearing support therefor in which the head is movable longitudinally; a rotatable member carried by said support and fixed against bodily movement relatively thereto; a spool-supporting fixture surrounding said head and carried by said rotatable member; a thread guide carried by said fixture and comprising an arm lying outside a spool mounted upon said fixture and extending forwardly toward the plane of the inner end of the said head.

10. In a ball-winding machine, the combination of a non-rotatable head; a bearing support therefor in which the head is movable longitudinally; a rotatable driving member carried by said bearing support and fixed against bodily movement relatively thereto; a spool-supporting fixture surrounding said head and carried by said rotatable member; a thread spool upon an axis common to said fixture; a guide arm carried by the fixture and lying wholly outside the spool, said arm extending forwardly beyond the plane of the inner end of said fixture; a thread-tensioning roller carried on the inner end of said arm; a guide arm removably secured to the inner end of the first arm and depending therefrom; and a roller at the free end of the second arm whereby, as the guide arms are rotated about the center line of said head, thread will be guided to and wound around a ball at the forward or inner end of the head.

11. In a ball-winding machine, the combination of two opposed non-rotatable heads; driven ball-supporting and driving rollers carried by each head; bearing mounts for each head permitting the heads to recede from each other as the diameter of the ball being wound increases; a rotatable spool-supporting fixture surrounding each head and normally held against movement along the axis of rotation of the fixture; and a thread guiding arm carried by each fixture and normally held against movement along its axis of rotation, said arms being rotatable about said heads to guide thread from spools mounted on said fixtures to and about a ball supported by said rollers, one of said heads and said associated elements being bodily movable away from the other for a sufficient distance to permit a

75

12

spool on either fixture to be removed lengthwise from the fixture.

12. In a ball-winding machine, the combination of a pair of opposed non-rotatable heads; ball-supporting and driving rollers carried by said heads and presenting spherical surfaces to a ball being wound; an oscillatable support for each roller; means for rotating said rollers about their individual axes and means for intermittently oscillating said roller supports, thereby to rotate the ball about different axes; a supply spool of winding thread; and mounting means for said supply spool for mounting the supply spool for rotation about an axis which at all times passes through the geometric center of the ball being wound, the axis of the spool coinciding with the said axes about which the spool rotates.

13. In a ball-winding machine, the combination of a pair of opposed non-rotatable heads; ball-supporting and driving rollers carried by said heads and presenting spherical surfaces to a ball being wound; an oscillatable support for each roller; means for rotating said rollers about their individual axes and means for intermittently oscillating said roller supports, thereby to rotate the ball about different axes; a supply spool of winding thread; and mounting means for said spool for mounting the spool for rotation about an axis which at all times passes through the geometric center of the ball being wound and coincides with the spool axis; and a thread guide, offset with respect to the supply spool and rotatable about the same axis as the supply spool for guiding the thread from the spool about the geometric center of the ball being wound during the said rotation of the ball.

14. In a ball-winding machine, the combination of a pair of opposed non-rotatable heads; ball-supporting and driving rollers mounted in each head and presenting spherical surfaces to a ball being wound; an oscillatable support for each roller; means for rotating said rollers about their individual axes and for intermittently oscillating said supports to rotate the ball successively about a plurality of axes; a thread supply spool; means for mounting the same for rotation about an axis which at all times passes through the geometric center of the ball being wound and coincides with the spool axis; a thread guide extending radially of the supply spool beyond the spool periphery; and means for rotating said guide about the axis of said spool to carry thread from the spool about the geometric center of the ball throughout the winding operation.

15. In a ball-winding machine, the combination of a pair of opposed non-rotatable heads; a supporting spindle for each head, said spindles being in axial alignment; rotatable, hemispherical ball-driving and supporting rollers carried by said heads; an oscillatable support for each of said rollers; driving means for rotating each of said rollers about its individual axis; means for intermittently oscillating said roller supports to rotate the ball successively about a plurality of axes; a thread supply in fixed position relatively to said heads and the ball being wound; a thread guide; means for rotating the same about the longitudinal axes of said spindles for guiding thread from said fixed supply source and carrying it about the ball; and means for varying the said driving means for said rollers relatively to the speed of rotation of the thread

13

guide, thereby to vary the spacing of the windings on the ball.

16. In a ball-winding machine, the combination of a pair of non-rotatable opposed heads; ball-supporting and driving rollers carried thereby, said rollers presenting spherical surfaces to a ball supported thereby; an oscillatable support for each of said rollers; means for rotating said rollers about their individual axes; and means for intermittently oscillating said roller supports to rotate the ball successively about a plurality of axes; a thread supply in fixed position relatively to said heads and to the ball being wound; a rotatable thread guide or flyer for guiding

14

thread from the said fixed supply source and carrying it about the ball; and means for varying the speed relation between the rollers and thread guide to vary the winding pattern produced on the ball being wound.
